SOUND ARRESTER IN THE VENTILATOR OF
SOUND-ARRESTING ROOMSMasaichi Tominaga, Kamata-ku, Tokyo, Japan;
vested in the Alien Property CustodianApplication July 15, 1941, Serial No. 402,549
In Japan August 5, 1940

2 Claims. (Cl. 181—50)

This invention relates to a sound-arresting structure consisting in the feature that the inner surface of the cylindrical ventilator in the sound generating room is all covered with a sound-arresting material, having, on the inner surface of the upper portion of the ventilator, a female screw shaped sound-absorbing wall projected inwardly, so as to eliminate sound waves in advancing them spirally.

The object of the present invention is to manufacture economically a sound-absorbing apparatus which completely prevents sounds from flowing outside the room.

The present invention is, with object of removing the foregoing defects, provided, on the roof or flank of the sound generating room, with one or more cylindrical ventilators each having, on the inner surface, a spirally disposed and inwardly projecting sound-absorbing wall whereby the ventilating cylinder is not only reinforced but the absorption of sounds and the escape of the air current are favorably increased.

The construction of the invention is illustrated in the accompanying drawing, in which:

Fig. 1 is a vertical cross-section of a sound generating room provided with the sound-absorbing apparatus according to the present invention partly showing a sectional elevation along a line C—C of Fig. 2.

Fig. 2 is a horizontal section taken on line A—A of Fig. 1.

Fig. 3 is a horizontal section taken on line B—B of Fig. 1.

Fig. 4 is a vertical cross-section taken on line E—E of Fig. 5 in case two paralleled spiral walls are provided.

Fig. 5 is a detail horizontal cross-section taken on line D—D of Fig. 4.

These figures illustrate the present invention by two examples. As regards the sound-arrester at the mouth of ventilator shown in Figs. 1, 2 and 3, there are provided at the four corners of the sound-arresting room 6 in which such noisy sound generators as machinery, engine, propeller for trial or talkie filming projector is held the cylindrical ventilators 2 erected on the floor and passing through the roof, each ventilator being cut away, in its inner part facing the room 6, to provide an air-inducing opening 3. All over the inner surface of the said ventilating cylinder, a sound-absorbing plate or lining 2' is pasted, and, the upper part of the cylinder i. e. the part above the ceiling of the room, is provided, on its inner wall, with a female screw shaped sound-absorbing wall 4 projecting inwardly a distance sub-

stantially equal to about a third the diameter of the cylinder. Such sound absorbing material may be Celotex, which is compressed bagasse, kapok or layers of cotton or burlap. The length 5 of the said screw shaped sound-absorbing wall is limited to one or, if necessary, to two or three convolutions. If the pitch of the screw shaped wall is steep, the ventilation is good, because the number of the wall convolutions is small, but 10 chances of repeated sound absorptions reduce. If the pitch is gentle, the absorption of sounds is complete, but as the number of convolutions or flights increases the ventilation is obstructed proportionally. The pitch and number of flights 15 in the said screw shaped sound-absorbing wall therefore depend on the strength of the sounds coming from the sound generator.

A sound observation booth 5 is built at the middle of the sound-arresting room 6, and, around 20 the booth 5, is placed a sound generator the sounds generated therefrom being observed by the observers in the booth 5.

As one of the modifications of the present invention, shown in Figs. 4 and 5, a central core on 25 column 7 having on its circumference a male screw shaped sound-absorbing wall 8 with the same pitch as that of the abovementioned female screw shaped wall 4 is set up coaxially in the said female screw shaped sound-absorbing wall 30 4. In this embodiment, since two spiral sound-absorbing walls are disposed in the ventilating cylinder, the effect on arresting sounds is far better than the case when a single wall is used.

According to the foregoing construction, sound 35 waves coming from the sound generator in the sound-arresting room 6 are induced to the air-inducing opening 3 directly or after reflection from the wall, door and ceiling of the sound-arresting room 6, and the sounds of short wave-length are partly absorbed and eliminated by the sound-absorbing wall 2' in the cylinder. The remaining sounds first collide with the lowest flight 40 of the screw or spiral shaped wall 4, and thereafter, repeated reflection between the flights 45 facing each other, causes the sounds to be continuously absorbed and completely eliminated.

The sounds of long wave-length which are difficult of elimination effect various reflections in several directions between the flights of the spiral 50 walls and create sufficient phasic differences among the sound-waves, in consequence of which the sounds are eliminated completely after their mutual interferences.

In the present invention, the passage of various 55 sounds of long and short wave-length is, as

abovementioned, spirally extended in order to effect complete sound-eliminating operations by especially complicating the reflection of the sounds in the said spiral passage, and, in addition thereto, it is free from obstruction to ventilation, and hence the present invention can be used more effectively than those hitherto used.

In case the entrance of the ventilator is formed in the side-wall of the sound-arresting room, the ventilating cylinder having the foregoing screw shaped sound-absorbing wall on the inner wall may be disposed horizontally. The ventilating cylinder having similar spiral wall may also be constructed on the ceiling instead of on the floor. The use of sound current regulators at the entrance of the ventilating cylinder makes the present invention more effective. The number and diameter of the said ventilating cylinder depend upon the area of the sound-arresting room and kinds of sounders.

I claim:

1. A sound-arresting structure for preventing the emanation of sounds from the ventilator of sound-arresting room having a cylindrical ventilator whose inner surface is covered with a

sound-arresting material, a female screw shaped sound-absorbing wall projected inwardly on the inner surface at the upper portion of the said cylindrical ventilator, and a column having a male screw shaped sound-absorbing wall with the same pitch as that of the said female screw shaped wall and set up coaxially within the latter wall so that these two spiral walls are alternately disposed in the ventilating cylinder the outer faces of the turns of the male screw extending outwardly so that their outer faces are substantially in alinement with the inner faces of the female turns and the turns of the male screw are located between the turns of the female screw.

10 2. In a structure of the character described, walls forming a cornered room, and shaped at the corners to form cylindrical ventilating shafts, communicating with the interior of the room at the bottom and with the outside air at the top, 15 the inner wall of said shaft being formed with a female screw, a male screw in said shaft with turns lying between the turns of the female screw and extending outward so as to cut off any direct 20 passage through the shaft.

MASAICHI TOMINAGA.
